(Cl. 66—95)

This invention relates to the production of knitted fabrics and is particularly concerned with a method and a machine for the production of tubular knit fabrics.

A serious difficulty in the production of tubular knit fabrics and indeed of fabrics generally, other than warp knit fabrics, lies in obtaining a fabric which will not run or ladder on breaking of a single stitch. It is an object of the present invention to produce a circular knit fabric which is free from the tendency normally present in knitted fabrics to run or ladder.

According to the present invention, in the knitting of a tubular fabric, loops in the fabric, after they have been formed by the needles, are individually and successively passed over the heads of the adjacent needles while still retained on the needles by which they were formed, the loops of each course being transferred progressively either back to the needles respectively preceding them, 10 or forward to succeeding needles. As a result of this, when the needle over the head of which a loop has been drawn next draws a loop, said loop is drawn through two earlier loops, one of which was formed on that needle and the other on an adjacent needle.

Thus in a tubular fabric resulting from the method of knitting outlined above, every loop forming part of the fabric may pass through two loops of the row of loops next below it, and 30 through every loop of the fabric there may pass two loops of the row next above it. If after its production the knitted fabric so formed is slightly damaged locally, although the damaged loops may release the loops through which they passed, 35 those loops in turn cannot release further loops, since the further loops are held not only by the released loops but also by other loops. In consequence, slight local damage does not produce a run or ladder in the fabric.

In a circular knitting machine according to the invention, there is provided, in addition to the circular series of needles, sinkers, and other knitting elements usually employed, a circular series of transfer points, each of which enters a loop immediately after such loop has been formed by a needle, and lifts it over the head of the adjacent needle while it is still retained by the needle on which it was formed. The adjacent 45 needle rises to receive the loop so transferred and the two needles concerned, in the subsequent knitting operation, each draw a new loop through the loop so transferred.

The circular series of transfer points is mounted 50 in a point cylinder whose motions are such as

to give the transfer points a slow circumferential movement relative to the needles, the transfer points either advancing slowly past the needles in the direction of knitting, or retiring slowly in the opposite direction, so as to effect the necessary transference of each loop picked up by a transfer point to the following needle, or to the preceding needle. In addition, the transfer points have a slight radial motion relative to the needles, such motion being effected either by cams appropriately disposed on the point cylinder, or by virtue of the different radii of the needle circle and the point cylinder.

Every loop in the fabric may be treated in this manner, the transfer points being so spaced and disposed that a point registers with each needle 15 as that needle forms a loop, or loops in selected parts of the fabric only may be so treated. Thus, by doubling the spacing of the transfer points, every alternate loop may be so treated, forming 20 a somewhat more open fabric than if all the loops were treated. Or, by omitting certain transfer points from the transfer point cylinder, or by otherwise putting them out of action, e. g. with a selective patterning mechanism, recurring patterns may be produced on the fabric. In the 25 latter case, in order to give the fabric ladder-proof qualities, it is desirable that, in each pattern repeat, at least one loop in every wale of the fabric should be transferred. Or again, 30 means may be provided for putting the transfer point mechanism completely out of action, whereby there may be produced on the fabric horizontal stripes visible because of the contrast 35 between the areas with transferred loops and the areas with normal loops. Further, in the case, for example, of a hosiery machine, other operations, such as forming heels and toes, may be carried out without any loop transfer.

Where a large circular machine having a number of yarn feeders is employed, one point cylinder may be provided for each feeder. In a hosiery machine having only one yarn feeder, one point cylinder is employed, which may be so mounted that it can be put out of action during 40 the operations of forming heels and toes on the machine.

By way of example a hosiery knitting machine according to the invention will now be described in greater detail with reference to the accompanying drawings in which

Fig. 1 is a side elevation of the upper part of the machine;

Fig. 2 is a plan view of Fig. 1;

Fig. 3 is another side elevation of the machine;

Figs. 4 and 5 show details of the machine; Fig. 6 is a view of the fabric formed according to the invention;

Fig. 7 is a sectional elevation;

5 Figs. 8 to 17 are details of the machine and its operation; and

Figs. 18 to 23 show details of an alternative form of construction and method of operation.

The machine comprises a frame 1 provided 10 with legs 2 and supporting a bed plate 3. A needle cylinder 8 is provided, having needles 9 held in tricks therein by means of springs 10. About the top of the needle cylinder is a sinker dial 11 carrying sinkers 12 which are pressed inwardly by 15 means of springs 13. In association with each of the needles 9 is a presser 14, a spring 15 being provided to hold the pressers in position. The needles are actuated by means of needle cams 16 working upon butts 17 on the needles 9. The 20 sinker cams 18 act on the butts 19 of the sinkers 12 and presser cams 20 act upon the pressers 14.

The needle cylinder 8 is rotated while the needle, sinker, and presser cams 16, 18, 20 remain stationary. The cylinder is supported in rotation on a bearing 21 carried by a bracket 22 (Fig. 3), which in turn is supported on a pillar 23 slidably mounted in bearings 24 and 25. The pillar 23 is capable of being moved slightly in a vertical direction so as to raise or lower the needle cylinder and to alter the length of the stitches formed by the needles 9. This is effected by 30 means of a lever 26 provided with adjustable followers 27 which are acted upon by a quality cam 28 mounted upon a shaft 29, driven by means 35 of a chain sprocket 30. The lever 26 is supported by the bearing 25 of the vertical pillar 23, and provided with a projection 31 acting upon a cam 32 fixed to the pulley 23 so that as the lever 26 is rotated slightly under the action of the quality 40 cam 28 the pillar 23 is raised or lowered.

The machine is driven by means of belt pulleys 33 mounted on the main shaft 34 of the machine, a bevel 35 on the shaft 34 meshing with a bevel 36 which is formed in one piece with a gear (not 45 shown) engaging with a gear 37 (shown in Fig. 7) at the bottom of the needle cylinder 8. A further bevel gear 38 is provided on the shaft 34 and is clutched thereto by means of a clutch 39 alternatively with the bevel gear 35 so that the machine 50 may be driven in either direction under the control of the clutch 39. The clutch 39 is in the form of a fork mounted upon a horizontally 55 slideable rod 40 which is engaged by a lever 41 pivoted at 42, the lower end of the lever being controlled by a cam 43 mounted upon the shaft 29.

All of the mechanism described above is that of an ordinary hosiery knitting machine, to which the mechanism for the purposes of the present invention is applied. The machine also comprises 60 other known mechanisms such as yarn guides 44 (Figs. 1 and 2) adapted to supply different yarns to the needles 9, the yarn guides being held in an inoperative position by means of springs 45, and brought into operative position when required by 65 means of levers 46 acted upon by cams 47.

For the purposes of the present invention there are employed transfer points 48 mounted in a point cylinder 49, the disposition of which is clearly shown in Fig. 7. The point cylinder 49 70 is mounted on and secured to a vertical shaft 50, provided at its upper end with a bevel gear 51 engaging with a bevel gear 52 mounted on a horizontal shaft 53. The shaft 53 is carried in a bracket 54. The shaft 53 is driven by means 75 of a bevel gear 55 engaging with a bevel gear 56

mounted on a shaft 57 carried in a bracket 58 which is secured at its lower end to the needle cylinder bearing 21 so that the whole assembly rises and falls with the needle cylinder 8 under the action of the quality cam 28 (Fig. 3). A gear 59 at the lower end of the shaft 57 engages with the gear 37 at the bottom of the needle cylinder. 5

As the needle cylinder rotates the transfer point cylinder 49 is caused to rotate also. The transfer points are provided with butts 60 engaging with transfer point cams 61 secured to the transfer point cylinder cover 62, the cams 61 being held stationary while the point cylinder 49 rotates. In this way, as the transfer point cylinder rotates, carrying the transfer points with 15 it, the transfer points are caused to rise and fall under the influence of the cams 61.

The relative motions between the needles 9 and the transfer points 48, and the cams producing such motions, are clearly shown in Figs. 8 20 to 16. The peripheral spacing and the peripheral speed of the transfer points 48 are slightly greater than those of the needles 9 so that the transfer points overtake the needles as both sets of elements rotate. 25

As is shown in Fig. 16 at the point 63, one of the transfer points 48 lies immediately behind one of the needles 9. At this point, as is shown in Figs. 9 and 13, the needle has just descended so as to draw a loop. In this position the transfer point descends under the influence of the cams 61 and enters the loop held by the needle 9 as is shown in Figs. 9 and 14. 30

The subsequent motions of the needle cylinder 8 of the transfer point cylinder 49 are such 35 that the transfer points overtake the needles to the extent of $1\frac{1}{2}$ needle spaces by the time they reach the point 64 shown in Fig. 16. At this stage, moreover, the eccentricity of the point cylinder with reference to the needle cylinder is such that 40 the transfer points 48, instead of being behind the needles as at the point 63 are alongside them.

The effect of this motion is clearly shown in Figs. 8 and 15, wherein the loops 65 carried by the needle 9 are drawn out over the head of the 45 adjacent needle. At this stage the needles 9 are again raised so that they enter the loops which have been drawn over them. Immediately afterwards, or at the same time, the transfer points 48 are also raised by the transfer point cams 61. 50 The result of these motions is that each of the needles is now passing through two loops and each of the loops has two needles passing through it.

When next the thread is supplied to the needle 55 by means of the yarn guides 44, each of the needles draws one loop through two of the preceding old loops. This one loop is then again stretched over the head of the adjacent needle by the operations described above and the needles rise again, 60 and so on.

The shapes of the cams necessary to produce the motions described above are shown in Figs. 10 to 12 which show the needle cams 16 and the needle butts 17 in appropriate relationship with 65 the sinker cams 18, the transfer point cams 61 and the transfer point butts 60. The points marked *a—a* on the three sets of cams exactly correspond to one another. It will be seen that at the point 66 (Fig. 11) the needle butts 17 are 70 pulled down by the needle cams 16 and shortly afterwards the transfer points 48 are pulled down at the point 67 (Fig. 10) by the transfer point depresser cam 66. The continued rotation of the needle cylinder and the transfer point cylinder 75

and the relative eccentricity of these members then operates to draw the loops into which the transfer points are successively inserted over the heads of the needles next to those on which such loops are held.

At the point 68 (Fig. 11) the needles are again lifted so as to be passed through the loops which have been drawn over their heads by the transfer points, and immediately afterwards, at the point 69 (Fig. 10) the transfer points are lifted. It will be observed that at the point 70 (Fig. 12) the sinkers are retracted (between the phases shown in Figs. 13 and 14) so as to leave room for the overtaking motion of the transfer points.

The resulting fabric is shown in Fig. 6 and it will be seen that each of the loops of which the fabric is formed is drawn through two loops of the preceding row of the fabric, while through each of the loops two loops are drawn. Thus the loop 71 in the middle of the fabric is drawn through the loop 72 and also through the loop 73. At the same time through the loop 71 the loops 74 and 75 are both drawn.

Instead of relying upon the eccentricity of the point cylinder with reference to the needle cylinder to bring the transfer points alongside the needles, a horizontally acting cam may be employed to push the transfer points outwards at the appropriate stages of the knitting operation. A modification of the transfer point cam system for this purpose is illustrated in Figs. 18 to 23.

Beneath the transfer point cylinder 49 is provided a cam 80 secured to the transfer point cylinder cover 62 by means of a bracket 81 as shown in Fig. 23. The cam 80, being secured to the cover 62, remains stationary like the cams 61. Four phases in the action of the cam 80 are shown in Figs. 18 to 21, while Fig. 22 shows the cam profile in relation to the needle heads and the transfer points.

Fig. 18 shows the position of the transfer points at the point 82 in Fig. 22 at which the cam is just about to come into contact with the transfer points. It will be seen that the transfer point butts 60 are rounded at their lower edges 83 in order to provide for a rocking motion of the transfer points. In Fig. 19 the cam 61 has caused the transfer point 48 to descend, and at the same time the cam 80 has pushed the transfer point 50 outwards to a position close behind the needles, as is shown at the point 84 in Fig. 22. It will be seen that the cover 62 is cut away inside at 85 in order to allow for this outward motion.

Between the points 84 and 86 in Fig. 22 the cam 80 permits the transfer points to withdraw slightly so that their actual motion is concentric with the needle cylinder, the withdrawal of the cam 80 between these two points compensating for the eccentricity of the point cylinder.

The position of the transfer point 86 of Fig. 22 is shown in Fig. 20. At the point 86 of Fig. 22 the faster motion of the transfer points has caused them to pass the needles to the extent of half a needle space. Between 86 and 87 the cam 80 once more presses out the transfer points so causing them to pass between the needles. Between 87 and 88 the transfer points travel behind the needles, and pass them to the extent of a whole needle space (making 1½ needle spaces in all). At 87, the cam 80 allows the transfer points to drop back to a position alongside and between the needle heads, as shown in Fig. 21.

It is at this point that the needles rise and pass through the loops which have been brought over their heads by the motions of the transfer

points described above. Immediately afterwards the transfer points are raised and the cam 80 allows the transfer points to withdraw horizontally at the point 89. The shaping of the inside of the cover 62 at the point 85 assists the cam 80 in the positioning of the transfer points.

Since it may not be desired that an article produced on the present machine should consist wholly of the fabric as illustrated in Fig. 6, means are provided for putting the point cylinder 49 out of action. The shaft 50 carrying the point cylinder 49 is mounted in a bracket 90 which is pivotally mounted in bearings 91 upon a shaft 92 to which the bracket 90 is secured. Clearance is provided at 93 between the bracket 90 and the bracket 54 carrying the shaft 53 so as to allow the whole point cylinder assembly to rock slightly about the bearings 91.

To effect this rocking motion a lever 94 is secured to the shaft 92, the lever 94 being engaged by a rod 95 operated by a bell crank lever 96 pivoted at 97. Between the rod 95 and the lever 94 there is a clearance 98 so as to provide for lost motion as shown in Fig. 4. A collar 99 on the rod 95 engages with the forked end 100 of a lever 101 pivoted at 102 on the shaft 92.

As is shown in Fig. 4 (a section through the line 5—5 of Fig. 2) the pivot 102 is secured to an eccentric sleeve 103 on the shaft 92. Outside the eccentric sleeve is a bearing 104 secured to a rod 105 which passes downwardly through the transfer point cover 62 and is attached to the transfer point depresser cam 106 (as shown in Figs. 7 and 14).

The rod 105 is broken in the middle, and provided with a turnbuckle 107, the two ends of the rod having screw threads of opposite hand, so that the exact position of the cam 106 can be adjusted.

The point cylinder assembly is held in operative position by means shown in Fig. 5, wherein 108 represents the needle circle. A spring 109 and a cap 110 fit inside a recess in the bracket 54, and bear against the bracket 90 which carries the shaft 50.

The bell crank lever 96 is operated by the clutch rod 40 as it moves towards the left to put into action the reciprocating motion of the knitting machine illustrated. When the clutch rod 40 is moved towards the left it acts through the bell crank lever to move the rod 95. By reason of the clearance 98 the rod 95 does not immediately act upon the lever 94 but first lifts the lever 101 and rotates the eccentric sleeve 103. The rotation of the eccentric sleeve 103 raises the bearing 104 and the rod 105 and lifts the transfer point depresser cam 106 so that this cam ceases to depress the transfer points.

After a short space of time, represented by the clearance 98, such transfer points 48 as have already been depressed by the depresser cam 106 are raised again at the point 69 (Fig. 14). At this stage the rod 95 reaches and raises the lever 94, thereby turning the shaft 92 and rocking the whole transfer point assembly about the bearings 91, removing the transfer points from the needles 9 which then operate as in an ordinary hose knitting machine.

In order to ensure that the loops are properly held and transferred by the transfer points 48, notches 111, as shown in Fig. 17, may be provided near the ends of the transfer points if desired.

What I claim and desire to secure by Letters Patent is:—

1. A circular knitting machine for the production of a non-laddering fabric, said machine comprising a series of needles, a yarn feed, means for actuating said needles successively to draw down loops of yarn fed by said yarn feed, and to rise again, a series of transfer points and means for entering said transfer points successively into the loops held by said needles and means for causing the transfer points to draw the loops so entered over the heads of adjacent needles before said needles are caused to rise again.
2. A circular knitting machine for the production of a non-laddering fabric, said machine comprising a circular series of needles, a yarn feed, means for actuating said needles successively to draw down loops of yarn fed by said yarn feed, and to rise again, at least one circular series of transfer points eccentric with respect to said series of needles, means for entering said transfer points successively into the loops held by said needles and means for causing the transfer points to draw the loops so entered over the heads of adjacent needles before said needles are caused to rise again.
3. A circular knitting machine for the production of a non-laddering fabric, said machine comprising a circular series of needles, a yarn feed, means for actuating said needles successively to draw down loops of yarn fed by said yarn feed, and to rise again, at least one circular series of transfer points eccentric with respect to said series of needles, means for entering said transfer points successively into the loops held by said needles and means for imparting to said transfer points a slow rotary motion relative to said needles so as to draw said loops over the heads of adjacent needles before said needles are caused to rise again.
4. A circular knitting machine for the production of a non-laddering fabric, said machine comprising a circular series of needles, a yarn feed, means for actuating said needles successively to draw down loops of yarn fed by said yarn feed, and to rise again, at least one circular series of transfer points eccentric with respect to said series of needles, means for entering said transfer points successively into the loops held by said needles and means for imparting to said transfer points a slow rotary motion relative to said needles in the direction of knitting so as to draw said loops over the heads of the next adjacent needles before said needles are caused to rise again.
5. A circular knitting machine for the production of a non-laddering fabric, said machine comprising a circular series of needles, a yarn feed, means for actuating said needles successively to draw down loops of yarn fed by said yarn feed, and to rise again, at least one circular series of transfer points eccentric with respect to said series of needles, means for entering said transfer points successively into the loops held by said needles, and means for causing the transfer points to draw the loops so entered over the heads of adjacent needles before said needles are caused to rise again, the eccentricity of said series of transfer points being such as to bring the transfer points alongside and between the needles as the needles rise again.
6. A circular knitting machine for the production of a non-laddering fabric, said machine comprising a circular series of needles, a yarn feed, means for actuating said needles successively to draw down loops of yarn fed by said yarn feed, and to rise again, at least one circular series of

transfer points eccentric with respect to said series of needles, means for entering said transfer points successively into the loops held by said needles, means for imparting to said transfer points a slow rotary motion relative to said needles so as to draw said loops past the heads of adjacent needles, and cam means for pressing said points outwards between the needles so that said loops are drawn over the heads of said adjacent needles before said needles are caused to rise again.

7. A circular knitting machine for the production of non-laddering fabric, said machine comprising a circular series of needles, means for rotating said series of needles, a yarn feed, stationary cam means for actuating said needles successively to draw down loops of yarn fed by said yarn feed and to rise again, at least one circular series of transfer points eccentric with respect to said needle series, means for causing said series of transfer points to rotate at a slightly different peripheral speed from said circular series of needles, and stationary cam means adapted to cause said points to descend and enter successively into the loops held by said needles, the eccentricity of said series of transfer points relative to said series of needles being such as to bring said transfer points between and alongside said needles after they have passed said needles to the extent of $1\frac{1}{2}$ needle spaces, and immediately before said needles rise again.

8. A circular knitting machine for the production of non-laddering fabric, said machine comprising a circular series of needles, means for rotating said series of needles, a yarn feed, stationary cam means for actuating said needles successively to draw down loops of yarn fed by said yarn feed and to rise again, at least one circular series of transfer points, means for causing said series of transfer points to rotate at a slightly different peripheral speed from said circular series of needles, stationary cam means adapted to cause said points to descend and enter successively into the loops held by said needles, and cam means adapted to press said transfer points outwards between the needles after the transfer points have passed said needles to the extent of $1\frac{1}{2}$ needle spaces and immediately before said needles rise again.

9. A circular knitting machine for the production of a non-laddering fabric, said machine comprising a series of needles, a yarn feed, means for actuating said needles successively to draw down loops of yarn fed by said yarn feed and to rise again, a series of transfer points and means for entering said transfer points successively into loops held by the said needles, means for causing the transfer points to draw the loops so entered over the heads of adjacent needles before said needles are caused to rise again, and means for causing the points to enter loops in selected portions of the fabric so as to effect loop transfer of such loops only.

10. A circular knitting machine for the production of a non-laddering fabric, said machine comprising a series of needles, a yarn feed, means for actuating said needles successively to draw down loops of yarn fed by said yarn feed, and to rise again, a series of transfer points, means for entering said transfer points successively into the loops held by said needles, means for causing the transfer points to draw the loops so entered over the heads of adjacent needles before said needles are caused to rise again, and means for putting said transfer points into and out of action so that

selected loops in the fabric are entered and transferred while the other loops are not transferred.

11. A circular knitting machine for the production of non-laddering fabric, said machine comprising a needle cylinder, a circular series of needles mounted therein, a yarn feed, means for actuating said needles successively to draw down loops of yarn fed by said yarn feed and to rise again, at least one transfer point cylinder eccentrically mounted with reference to said needle cylinder, a circular series of transfer points, means for entering said transfer points successively into loops held by said needles, means for causing the transfer points to draw the loops so entered over the heads of adjacent needles before said needles are caused to rise again, and means for pivoting said transfer point cylinder inwards with reference to the needle cylinder so as to remove said transfer points from engagement with the needles.

12. A circular hosiery knitting machine for the production of non-laddering hose, said machine comprising a needle cylinder, a circular series of needles mounted therein, a yarn feed, means for actuating said needles successively to draw down loops of yarn fed by said yarn feed and to rise again, a transfer point cylinder eccentrically mounted with reference to said needle cylinder, a circular series of transfer points, means for en-

tering said transfer points successively into loops held by said needles, means for causing the transfer points to draw the loops so entered over the heads of adjacent needles before said needles are caused to rise again, and means for pivoting said transfer point cylinder inwards with reference to the needle cylinder so as to remove said transfer points from engagement with the needles.

13. A circular knitting machine for the production of a non-laddering fabric, said machine comprising a needle cylinder, a circular series of needles mounted therein, a sinker dial, a circular series of sinkers radially mounted therein, a yarn feed, means for actuating said needles successively to draw down loops of yarn fed by said yarn feed, and to rise again, a series of transfer points and means for entering said transfer points successively into the loops held by said needles, means for causing the transfer points to draw the loops so entered over the heads of adjacent needles before said needles are caused to rise again, and means for raising and lowering said needle cylinder and said transfer points together relatively to said sinkers so as to vary the length of the stitches formed by said needles, the transfer points remaining in correct vertical register with said needles during such raising and lowering.

WILLIAM HENRY BOALER.
